175,689

GIRDLE OR SIMILAR ARTICLE

Gabriel Leventhal, Great Neck, N. Y.

Application January 10, 1955, Serial No. 33,907

Term of patent 14 years

(Cl. D20—2)

Figure 1 is a front elevational view of a girdle, or similar article, showing my new design; and

I claim:

The ornamental design for a girdle or similar article, as shown.
